ABSTRACT OF THE DISCLOSURE

An apparatus for sequentially dispensing void markers against moving webs of paper or other material for the purpose of marking voids or other irregularities as detected in the web. A marker transport element is effective to accelerate the marker from a remote stationary position in a magazine to a speed approximately equal to the speed of the moving web and then urges the marker against the web for attachment to it.

BACKGROUND OF THE INVENTION

In the manufacture, handling and inspection of web materials, such as paper, it is often necessary to mark selected sections of a continuous strip or web of the material. Identification of these sections may be done for a variety of reasons. For example, web materials manufactured and coated using present commercial processes often have flaws, voids or other irregularities in their webs or coated surfaces. Such irregularities make these web material unsatisfactory for many uses and it is therefore necessary that the irregularities be repaired or that the sections of the material including the irregularities be removed.

Inspection of the web material is usually conducted as it comes off the producing or coating machine and before the material is wound onto a roll for storage or shipment. Inspection of the completed web material prior to winding it onto rolls has been accomplished by visual inspection by the equipment operator or by detectors or other sensing devices. The marker in the form of a tag or other piece of marking material is inserted at the appropriate time between the winding roll and the web material. The marker or tag is inserted in such a manner that one of its ends protrudes past the edge of the wound roll thus providing a ready identification of the section having the detected irregularity. The marker is held in position by the forces of friction and pressure exerted by rolled web. A roll of material wound and marked in this manner is usually transported to another location where the marked irregularities are either repaired or the section including the irregularity is removed.

These conventional practices require placing the marker on the web in the area immediate to the winding roll. This requirement limits positioning and use of the marker and has the further disadvantage that it is a dangerous area for manual delivery of markers. This area which is sometimes known as the "nip" area is a dangerous area to place a hand or arm because the web material or rotating roll will from time to time come in contact with the hand or arm, causing it to move farther into the nip where the squeezing action of the winding roll and the web material result in injury.

SUMMARY OF THE INVENTION

The present invention provides a device that is not limited to placing markers in the nip area but delivers markers into engagement with the moving web at any selected position along the moving web.

Broadly, the present invention comprises an apparatus for selectively attaching markers to a moving web where

2

the markers are capable of attachment to the web by the application of pressure, which apparatus includes means for selectively dispensing in a sequence a plurality of markers at a position remote from the moving web, marker transport means positioned to transport the dispensed markers from the remote position and deposit them on the moving web, power means for moving the marker transport means between the remote position and a position near the moving web, and regulating means for regulating the speed of the transport means to cause the marker to be deposited on and pressed against the moving web at a speed substantially equal to the speed of the web.

It is a feature of the invention that markers may be attached to the moving web at any position along the web travel by mounting the apparatus described at the selected position and it is also a feature that the apparatus may be readily and quickly adjusted to permit attachment of markers at various speeds of web movement.

BRIEF DESCRIPTION OF THE DRAWING

In the drawing FIG. 1 is a side elevation view of the apparatus without the marker magazine and FIG. 2 is an enlarged perspective view of the apparatus.

DESCRIPTION OF THE PREFERRED EMBODIMENT

In the drawing the moving web 1 travels, as shown by the arrow (FIG. 1), from left to right at a selected speed. It is contemplated that high and low speed webs may be marked with the present invention; for example, conventional paper web handling apparatus move paper webs at speeds varying from about 800 to 3,000 feet per minute. Stationary shoe 2 provides a supporting surface for the web as it passes through the delivery position 20 of the apparatus. Vertically positioned frame 3 has arm 4 mounted for pivotal movement about axis pin 5. Arm 4 which is held in its rest position by spring 9 is capable of being moved downward to a vertical position (broken lines) by solenoid unit 6 consisting of a coil 7 and a movable core 8. Core 8 is connected to arm 4 through coupling 28.

An arcuate marker support ramp 10 is mounted on frame 3 with its lower end terminating at the delivery position 20 adjacent the moving web 1 and above the stationary shoe 2. As shown in FIG. 2, a marker 13 is placed against ramp 10 by a magazine or rotatable drum unit 11 having grips 12 and the marker is held in the position until it is transported down and onto the moving web. Marker 13 has adhesive 14 applied to one of its end portions to provide for attachment of the marker to the web at delivery position 20. Ramp 10 is slotted to prevent adhesive 14 from interfering with the motion of the marker during its travel toward the web to permit finger 16 to position itself against the side of the marker to permit the marker to be pushed by the finger. The marker may be attached to the web by any other suitable means such as mechanical fasteners provided that the attachment may be accomplished by placing the marker in pressure engagement with the moving web.

The marker is removed from its grip 12, transported down ramp 10 and applied to the moving web 1 by finger 16 and resilient pusher 15 both of which are mounted on end plate 17 which in turn is secured to the lower end of arm 4. Finger 16 is held in its pivotable position, as shown in FIG. 1, by spring 18 such that the lower portion of finger 16 is farther from delivery position 20 than that portion of the finger above pivot pin 19. The lower end portion 33 of finger 16 includes two prongs, one adapted to move in slot 30 and the other to move along the outside edge of ramp 10. An adjustable stop 21 mounted on frame 3 above delivery position 20 engages the upper por-

tion of pivotable finger 16 as it nears the bottom of its travel causing the lower portion of the finger to accelerate to a linear speed substantially the same as that of the moving web. Stop 21 is vertically adjustable to vary the linear speed of the lower portion of finger 16.

Resilient pusher 15 initially holds marker 13 against ramp 10 until it is pushed to the lower end of the ramp by finger 16 where the pusher functions to apply pressure to adhere the marker to the moving web.

Drum unit 11 is rotated about shaft 22 by racket arrangement 23 and rocker arm 24. Rocker arm 24 is rocked by reciprocating connector 25 driven by solenoid 27. Each reciprocation of connector 25 rotates drum unit 22 one quarter turn and places another marker on the ramp with the adhesive area of the marker over the ramp slot. The drum unit or magazine and its drive means are supported by conventional means not shown.

In the operation of the apparatus, the coil box 7 of solenoid unit 6 is energized through a control switch (not shown) which is operated by the equipment operator or by an automatic device detecting a void in the moving web. The electrically-generated forces of coil box 7 cause movable core 8 to move rapidly downward from left to right as viewed in FIG. 1. Coupling 28 permits arm 4 to swing freely about pivot pin 5 in response to linear movement of movable core 8. Arm 4 continues to move downward until it strikes button 29 which energizes solenoid 27 to move a new marker into place before pivotal arm 4 returns to its rest position.

During its downward movement arm 4 carries lower finger end 33 including the one prong which moves into and along slot 30 of ramp 10 and the other prong which moves alongside the ramp, both prongs engaging and pushing marker 13 out of grip 12 and down the ramp. Pusher 15 holds the marker in front of end 33 and against the surface of ramp 10. As the marker leaves the ramp and comes in contact with the web the pusher causes the adhesive portion 14 of the marker to adhere to the web. Shoe 2 supports the web under the delivery position 20 as the pusher urges the marker downward. Additional markers are placed in the empty grips of the magazine as required.

The apparatus of the invention is adjustable to permit the speed of the finger to be varied to accommodate for varying speeds of web travel. In the embodiment shown in the drawings, the speed of the finger is varied by adjusting the vertical position (H) of stop 21. In the rest or upper position of the arm 4 spring 18 holds finger 16 in a position at an angle to arm 4. The vertical position of stop 21 determines how fast the finger is moved to its final vertical position (dashed line FIG. 1) after it has engaged the stop 21 and completed its downward travel. If stop 21 is in a high position, the time taken by finger 16 to turn and reach its vertical position is greater than if the stop is in a low position. The more time the finger has to move to its final position the slower lower end 33 will be moving as the marker is deposited on and adhered to the web. The less time the finger has to rotate about pivot 19 the faster the lower end will be moving. The stop is preferably adjusted to provide a lower end finger speed approximately equal to the speed of the moving web.

The closing of switch 29 energizes solenoid 27 (FIG. 2) causing rod 26 to move upward rotating magazine or drum unit 11 a quarter of a turn (90°) and placing another marker against ramp 10. Upon the de-energization of coil box 7 and the dissipation of kinetic energy of the arm and finger as they impact switch 20 and stop 21, spring 9 returns the arm to its rest position. Finger 16 and the pusher 15 move back over the marker just placed on the ramp by the marker holder. Finger 16 pivots about pin 19 as necessary to move back over the marker without removing it from the grip 12. The apparatus is then ready for another cycle.

I claim:

1. A device for depositing a marker on a moving web comprising,

(a) support means for supporting the marker remote from the moving web,

(b) marker transport means positioned to transport a marker from the support means to a position adjacent the moving web, said transport means in turn comprising,

(i) a marker carrying element pivotably mounted on said marker transport means, said element being capable of turning movement relative to said transport means,

(c) adjustable turning means for turning the pivotable marker carrying element to selectively adjust the speed of the marker carried by the element to be substantially the same as the speed of the web whereby a marker is removed from the support means, caused to move at a speed substantially the same as the speed of the moving web, and deposited on the moving web.

2. The device of claim 1 wherein the marker carrying element has an upper end and a lower end for engaging the marker and wherein the adjustable turning means is a stationary stop means suitably positioned adjacent the moving web such that the upper end of the marker carrying element strikes the stop means as the element moves to its position adjacent the moving web causing the lower end of the element to pivot thereby increasing the speed of the lower end of the element.

3. A device for sequentially delivering and attaching to a moving web a plurality of adhesive coated markers comprising,

(a) a frame,

(b) an inclined ramp supported by the frame and positioned with its lower end adjacent a selected section of the moving web,

(c) a rotatable magazine for holding a plurality of markers positioned to selectively deliver markers onto the ramp,

(d) a pivotable reciprocating marker transport element positioned on the frame for movement along the surface of the ramp to engage with and transport a marker to the moving web at approximately the speed of the web,

(e) a resilient pusher element mounted on the transport element to press the adhesive coated marker against the moving web,

(f) power means for operating the rotatable magazine to deliver a marker to the ramp,

(g) control means to activate the magazine when the transport element moves along the ramp,

whereby a sequence of markers are positioned for transport and are transported to and attached to the moving web.

4. A device for sequentially delivering and attaching to a moving web a plurality of markers capable of connecting themselves to a web by being pressed against the web comprising,

(a) support means including a ramp positioned with its lower end adjacent the moving web for supporting a marker remote from moving web,

(b) a marker magazine and delivery means for selectively delivering markers to the support means,

(c) transport means including a pivotable reciprocating arm capable of movement toward and away from the web,

(d) means for pressing each marker against the web, and

(e) control means actuated by the transport means to cause the marker delivery and magazine means to deliver another marker to the support means,

whereby a plurality of markers are sequentially delivered to and pressed against a moving web.

5. A device for sequentially delivering and attaching to a moving web a plurality of markers capable of connect-

ing themselves to a web by being pressed against the web comprising,

- (a) support means capable of supporting a marker remote from the moving web,
- (b) a marker magazine and delivery means for selectively delivering markers to the support means,
- (c) transport means for transporting the markers from their remote position to a position adjacent the moving web in a direction substantially parallel to the direction of movement of the moving web and with sufficient acceleration to cause the markers to move at speeds substantially equal to the speed of the web,
- (d) means for pressing the marker against the web as it moves at such speed which is substantially equal to the speed of the web, and
- (e) control means actuated by the transport means to

cause the marker delivery and magazine means to deliver another marker to the support means, whereby a plurality of markers are sequentially delivered to and pressed against a moving web.
